UNITED STATES PATENT OFFICE

GLADEON M. BARNES, OF THE UNITED STATES ARMY, HASTINGS, MICHIGAN

GUN

Application filed December 10, 1930. Serial No. 501,322.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The subject of this invention is a gun particularly designed as a modification of co-pending application Serial No. 413,117, filed December 10, 1929, and as an improvement on the type of mechanism originating in 10 Patent No. 749,215 of 1904.

The system of controlling the movement of a gun as proposed in the patent contemplates the reversal of a portion of the gases of discharge and their collection for utilization by compressive action and reaction to retard the gun in recoil and restore it to battery.

In order to take full advantage of the merits of this system and adapt it for practical application to modern high power guns it becomes necessary to introduce means for exercising additional and more accurate control of the gases.

Accordingly, the improvements of the 25 present application are directed to provisions for regulating the length of recoil, the velocity of recoil and counterrecoil, and the power of buffer mechanisms.

With the foregoing and other objects in 30 view, the invention resides in the novel arrangement and combination of parts and in the details of construction hereinafter described and claimed, it being understood that changes in the precise embodiment of 35 the invention herein disclosed may be made within the scope of what is claimed without departing from the spirit of the invention.

A practical embodiment of the invention 40 is illustrated in the accompanying drawings, wherein:

Fig. 1 is a more or less diagrammatic illustration in the nature of a longitudinal sectional view of the improved recoil and counterrecoil mechanism;

45 Fig. 2 is a transverse sectional view showing a method of arranging the various elements with respect to a gun for establishing gas communication between the gun and recoil cylinder;

50 Fig. 3 is a longitudinal sectional view of

the recoil cylinder showing alternate arrangements for effecting regulation of the gases;

Fig. 4 is an enlarged longitudinal sectional view of the valve in the auxiliary chamber 55 of Fig. 2;

Fig. 5 is a similar view of the valve in the auxiliary chamber of Fig. 3;

Fig. 6 is a more or less diagrammatic illustration in the nature of a longitudinal sectional view showing the means for holding the gun in battery;

Fig. 7 is a fragmentary view similar to Fig. 6 showing the holding means in released position;

Fig. 8 and 9 are sectional views on the corresponding lines of Figs. 6 and 7; and

Fig. 10 is a sectional view on the line 10-10 of Fig. 6.

Referring to the drawings by characters 70 of reference:

In Figs. 1 and 2 there is shown a gun 11 having slides 12 whereby it is reciprocally mounted in the conventional manner in a cradle 13. A recoil and counterrecoil cylinder 14 supported by hangers 15-15 is secured to the gun lug 16 through its rear cylinder head 17 and the nut 18 so that it partakes of the movement of the gun.

The interior of the cylinder is in communication with the interior of the gun, a convenient method of structurally accomplishing this end being shown in Fig. 2, wherein a passage 19 in a valve block 15a associated with the hanger 15 is open to an outlet passage 20 in the gun and an inlet passage 21 in the cylinder. By this provision the rapidly expanding gases of discharge may be conducted from the bore of the gun to the cylinder.

The passage 19 is provided with a valve seat 22 intermediate the passages 20 and 21 so that communication may be interrupted by a valve 23. A spring 24 seated on an element of the cylinder bears against a spur gear 25 fast on the valve stem and normally tends to move the valve to open position. Such movement is opposed by a nut 26 threaded on the valve stem and receivable in a recess 27 in the hanger 15. The nut 26 is held against 100

rotation by a key 28 with the result that rotation of the valve through the gear 25 serves to advance or retract with respect to the valve seat. When the gun is in battery 5 the valve stem is arranged to engage a buffer rod 29 slideable in the cradle and having resistance supplied by Belleville washers 30. The rod 29 serves to positively maintain the valve 23 open whenever the gun is in bat- 10 tery.

Parallel to and in communication with the passage 19 through a port 31 is a passage 32 open to a conduit 33. A valve seat 34 in the passage is provided to receive a valve 35 15 which is similar to the valve 23 and has a spur gear 36 meshing with the spur gear 25. The stem of the valve 35 is slideable in a gear 37 meshing with a gear 38 fast on a shaft 39. This shaft is controlled by gearing 40 in the 20 well known manner when the cradle is moved in elevation, the purpose being to effect a variable length of recoil by regulating the volume of gas introduced into the cylinder.

The conduit 33 leads to a valve block 41 25 secured to the rear end of the cylinder and is in communication with a passage 42 in the block that leads to the cylinder. The passage 42 is extended beyond its junction with the conduit to lead to the atmosphere, and is 30 offset to form a seat for an adjustable relief valve 43 normally held closed by a spring 44.

Within the cylinder is a hollow piston rod 45 secured at its forward extremity to an ele- 35 ment of the cradle. The piston head 46 is spaced from the cylinder head 17 to constitute a buffer chamber 47 and is provided with a passage 48 and valve 49 to permit a controlled admission of gases into the buffer 40 chamber. When the gun is in battery the piston head is disposed between the gas pas- 45 sages 21 and 42. The valve 49 threadedly engages a plug 50 and is provided with a slotted head 51 to receive a screwdriver 45 which may be introduced through a normally closed aperture 52 in the cylinder head 17.

Secured to the forward cylinder head 53 is an annular casing 54 spaced both from the wall and the head of the cylinder 14 and 50 from the piston rod 45 and providing a cham- 55 ber 55. As shown in Fig. 4 a hollow plug 56 secured in the rear end wall 57 of the casing is formed with a valve seat 58 on its inner end and an indented outer end 59. A rod 60 disposed within the casing has a portion 61 extending through the plug 56 and spaced therefrom at one or more points to provide a gas passage 62. A valve head 63 formed 60 on the rod is engageable with the seat 58 to close the passage 62 and limit rearward move- 65 ment of the rod while a nut 64 threaded on the outer extremity of the rear portion 61 is engageable with the indented end of the plug to limit forward movement. The rear portion 61 of the rod is provided with a pas-

sage 65 establishing communication between the chamber 55 and the cylinder.

The forward end of the rod extends through an aperture in the forward end plate 66 of the casing and is movable into and out of the mouth of a vent passage 67 whose exit is regulated by an adjustable valve 68. This arrangement is of especial benefit in a gun having a variable length of recoil. 70

A modified form of this arrangement is 75 shown in Fig. 5 wherein the vent 67 and the forward end of the rod are eliminated so that venting must take place through the inlet 65. This affords a regulation of the gases available for counterrecoil and is especially suited to a mechanism having a non-variable stroke. 80

There is also shown in Fig. 3 a modified method of adjusting the valve 49a in the piston head. The valve has a reduced inner end 69 engageable in the forked end of a rod 70 journaled in the hollow piston rod and projecting from the forward end thereof to be associated with gearing 71 actuated through a shaft 39a in the same manner as the shaft 39. 85

Because the structure of the cylinder and piston are not such as to retain the gases indefinitely, it is necessary to provide means for holding the gun in battery. A provision for accomplishing this object is illustrated in Figs. 6 to 10 and consists of a piston 72 mounted in a housing 73 forming an element of the cradle and normally maintained in the forward position by a spring 74 having sufficient capacity to support the gun in all positions of elevation. The piston is connected to the recoil cylinder by means of a pawl 75 mounted in a forked block 76 secured to the rear end of the piston and arranged to engage teeth 77 on the cylinder. The pawl is normally held in tooth-engaging position by a plunger 78 and is adapted to be rotated out of engagement when, in partaking of the rearward movement of the gun in recoil, it rides on a cam surface 79 formed in the housing 73. 95

As seen in Fig. 8 one of the forks of the block 76 is extended and includes a transversely disposed casing 80 in which is mounted a plunger 81. The plunger is normally urged by its spring 82 towards the pawl which has an aperture 83 in line therewith when the pawl is rotated by the cam 79. An arm 84 secured to the outer end of the plunger (Fig. 10) overlies the casing 80 and has a tongue and groove connection 85 therewith so that it may reciprocate with the plunger. 110

In a casing 86 formed in the housing 73 115 there is mounted a plunger 87 acting at right angles to the plunger 81 and arranged to engage the arm 84 and oppose movement of the plunger 81 when the piston 72 is fully forward (Fig. 8). Upon rearward move- 120 130

ment of the piston the plunger 81 is released so that it will be free to enter the aperture in the pawl and thereby hold the pawl out of engagement with the teeth 77 while the gun and cylinder move in recoil. When all of the teeth have cleared the pawl a lug 88 on the cylinder strikes the arm 84 deflecting it laterally to withdraw the plunger 81 from the pawl and permitting the plunger 87 to reengage the arm 84 and hold the plunger 81 in withdrawn position. The pawl is then free to be restored to the tooth-engaging position and when the gun and cylinder complete their counterrecoil movement the pawl will engage one of the teeth and thereby connect the cylinder to the piston. The forward movement of the piston under the influence of its spring is arrested by a buffer consisting of a series of resilient washers 89.

In operation when the gun is fired, a portion of the rapidly expanding gases of discharge will be delivered through the passages 20, 19 and 21 and past the valve 23 to the cylinder 17 which by virtue of its attachment to the gun is partaking of the recoil movement. A part of the energy of recoil is absorbed by turning the high velocity gases rearward through 180°, the gases being obliged by their reversal to exert a forward pressure on the recoiling members.

During the initial stage of recoil and counterrecoil when the pressure in the cylinder exceeds the rapidly decreasing pressure in the bore of the gun it effects the closing of the valve 23. The gases confined in the cylinder will be compressed as the forward end of the cylinder approaches the stationary piston head 46 and will act to yieldingly check the recoil of the gun.

A portion of the gases delivered to the passage 19 will flow past the valve 35 and through the conduit 33 to be admitted to the buffer chamber 47 established in rear of the piston head. The valve 35 will be closed when the pressure in the buffer chamber becomes superior to bore pressure. An additional supply of gas is admitted into the buffer chamber from the forward or high pressure side of the cylinder by means of the passage 48 and valve 49. The controlled delivery of gases to the buffer chamber and the adjustment of the valves 35 and 49 maintain the chamber at a low pressure to enable the higher compressed gases in the forward part of the cylinder to restore the gun to battery.

The compressed gases in the high pressure side of the cylinder are forced into the annular casing through the passage 62 and 65 so that at the termination of the recoil stroke the pressures in the cylinder and the casing are equalized.

At the commencement of the counterrecoil stroke the pressure in the cylinder decreases so that the pressure in the annular casing moves the rod 60 and seats the valve 63. The

rod is also withdrawn from the vent 67 to establish communication between the cylinder and the atmosphere through the valve 68. The automatic action of this mechanism operating according to differential pressures serves as a means of regulating the velocity of recoil and counterrecoil the size of the passage 65 and the lift of the valve 67 being determining factors.

Where a constant length of recoil is to be employed, as opposed to a variable length of recoil, the vent 67 may be eliminated as shown in Fig. 5.

During the final portion of the counterrecoil stroke the piston compresses the gases in the buffer chamber and establishes such an equalization of pressures on either side thereof as will enable the gun to be eased into battery. At the end of the counterrecoil all the gases escape from the cylinder, the valves 23 and 35 being normally open. The buffer 29 is arranged in the path of the valve 23 so that when the gun arrives in battery, it will positively open the valve against any pressure that may be tending to hold it closed.

From the foregoing it will be seen that means are provided for regulating the rate of flow and the volume of the gases as they are admitted to or exhausted from the cylinder. In this way the length of the recoil and the velocity of recoil and counterrecoil can be positively and accurately regulated, the adjustments being varied according to the elevation of the gun.

I claim:

1. In a gun, a cradle, a barrel reciprocally mounted in the cradle, a cylinder movable with the barrel, a stationary piston in the cylinder defining a main compression and a buffer chamber, a valved communication between the chambers, a valved communication between the barrel and each of the chambers, means operable on elevating the barrel for automatically regulating the valves of said latter communications, means effective when the barrel is in battery for positively opening the valve in the communication with the compression chamber, a relief valve for the buffer chamber, a relief valve for the compression chamber, an auxiliary compression chamber, and means for controlling the flow of gases between the auxiliary and the main compression chamber and operable through differential pressures to control venting of the main compression chamber.

2. In a gun, a cradle, a barrel reciprocally mounted in the cradle, a cylinder movable with the barrel, a stationary piston in the cylinder defining a main compression and a buffer chamber, a valved communication between the chambers, a valved communication between the barrel and each of the chambers, means for regulating the valves of said latter communications, means effective when the

barrel is in battery for positively opening the valve in the communication with the compression chamber, a relief valve for the buffer chamber, a relief valve for the compression chamber, an auxiliary compression chamber and means for controlling the flow of gases between the auxiliary and the main compression chamber and operable through differential pressures to control venting of the main compression chamber.

3. In a gun, a cradle, a barrel reciprocally mounted in the cradle, a cylinder movable with the barrel, a stationary piston in the cylinder defining a main compression and a buffer chamber, a valved communication between the chambers, a valved communication between the barrel and each of the chambers, means for regulating the valves of said latter communications, a relief valve for the buffer chamber, a relief valve for the compression chamber, an auxiliary compression chamber, and means for controlling the flow of gases between the auxiliary and the main compression chamber and operable through differential pressures to control venting of the main compression chamber.

4. In a gun, a cradle, a barrel reciprocally mounted in the cradle, a cylinder movable with the barrel, a stationary piston in the cylinder defining a main compression and a buffer chamber, a valved communication between the chambers, a valved communication between the barrel and each of the chambers, means for regulating the valves of said latter communications, means effective when the barrel is in battery for positively opening the valve in the communication with the compression chamber, a relief valve for the buffer chamber, and a relief valve for the compression chamber.

5. In a gun, a barrel reciprocally mounted in the cradle, a cylinder movable with the barrel, a stationary piston in the cylinder defining a compression and a buffer chamber, a valve block associated with the barrel and cylinder communicating passages in the valve block, means for introducing gases from the barrel to one of said passages, means for introducing gases to the compression chamber from one of said passages and to the buffer chamber from the other passage, a valve for each of the passages, meshed gears on the valves, a spring acting against each gear to normally hold the valve open, a nut threaded on each valve and having sliding and non-rotating connection with the valve block, means operable on elevating the barrel for rotating one of the valves, and means effective when the barrel is in battery for positively opening one of the valves.

6. In a gun, a barrel reciprocally mounted in the cradle, a cylinder movable with the barrel, a stationary piston in the cylinder defining a compression and a buffer chamber, a valve block associated with the barrel and

cylinder, communicating passages in the valve block, means for introducing gases from the barrel to one of said passages, means for introducing gases to the compression chamber from one of said passages and to the buffer chamber from the other passage, a valve for each of the passages, and means operable on elevating the barrel for simultaneously adjusting the setting of the valves.

7. In a reciprocating gun, a recoil mechanism utilizing the compressive action and reaction of the gases of discharge to check recoil and restore the gun to battery, means for introducing the gases to the recoil mechanism at a plurality of points, a pair of valves controlling the rate of introduction of the gases, meshed gears on the valves, a spring acting on each gear to normally hold the valve open, a slidably and non-rotatably mounted nut threaded on each valve, and means operable on elevating the barrel for rotating one of the valves.

8. In a reciprocating gun, a recoil mechanism utilizing the compressive action and reaction of the gases of discharge to check recoil and restore the gun to battery, a gas passage leading from the gun to the recoil mechanism, a valve for closing said passage, a spring normally urging the valve open, means for limiting movement of the valve in opening and means operable on elevating the barrel for adjusting the limiting means.

9. In a reciprocating gun, a cylinder movable with the gun, a stationary piston in the cylinder defining a compression and a buffer chamber, a valved communication between the chambers whereby gases are transferable from the compression chamber, and a valved communication between the gun and each of the chambers.

10. In a reciprocating gun, a cylinder movable with the gun, a stationary piston in the cylinder defining a compression and a buffer chamber, a valved communication between the chambers whereby gases are transferable from the compression chamber, and means for admitting gases from the gun to each of the chambers.

11. In a reciprocating gun, a cylinder movable with the gun, a stationary piston in the cylinder, means for transferring gases of discharge from the gun to the cylinder for compressive action and reaction, an annular casing secured to the forward cylinder head and embracing the piston, a gas passage establishing communication between the cylinder and casing, a valve operable through differential pressures and closing the gas passage when the pressure in the casing is superior to the pressure in the cylinder, a vent for the cylinder controlled by the valve and normally open when the valve is in position to close the gas passage, and a duct in the valve establishing communication between the cylinder and casing at all times.

12. In a reciprocating gun, a cylinder movable with the gun, a stationary piston in the cylinder, means for transferring gases of discharge from the gun to the cylinder for compressive action and reaction, an annular casing secured to the forward cylinder head and embracing the piston, a pressure operated valve controlling the flow of gases between the cylinder and casing, a vent for the cylinder controlled by the valve, and a duct in the valve for establishing communication between the cylinder and casing at all times.

13. In a reciprocating gun, a cylinder movable with the gun and having a vent, a stationary piston in the cylinder, means for transferring gases of discharge from the gun to the cylinder for compressive action and reaction, a casing movable with the cylinder and having communication therewith at all times, and a pressure operated valve controlling the vent of the cylinder and the flow of gases between the cylinder and casing.

14. In a reciprocating gun, a cylinder movable with the gun, a stationary piston in the cylinder defining a main compression chamber, an auxiliary compression chamber, and means operable through differential pressures for controlling the flow of gases between the auxiliary and the main compression chamber, and the venting of the main compression chamber.

15. In a reciprocating gun, a cylinder movable with the gun, a stationary piston in the cylinder defining a main compression chamber, an auxiliary compression chamber, and means operable through differential pressures for controlling the flow of gases between the auxiliary and the main compression chamber.

16. A cradle, a recoil gun mounted thereon, means for checking the gun in recoil and restoring it to battery, a gun-holding piston carried by the cradle, a pawl on one end of the piston, means for normally holding the pawl in gun engaging position, a fixed cam for disengaging the pawl on recoil, a plunger carried by the piston and engageable with the pawl to hold it disengaged, means for holding the plunger against rotation, a lug on the gun for moving the plunger out of engagement with the pawl, and means carried by the cradle for holding the plunger disengaged from the pawl.

17. A cradle, a recoil gun mounted thereon, means for checking the gun in recoil and restoring it to battery, a gun-holding member carried by the cradle, a movable gun-engaging pawl on said member, means for disengaging the pawl from the gun during recoil movement of the gun, means carried by the gun-holding member for holding the pawl disengaged, and means for inoperating the holding means.

GLADEON M. BARNES.
